T. W. THOMPSON

BLACK BOARD CLEANER

Filed Oct. 28, 1925

WITNESS:

T. W. Thompson
INVENTOR

BY *Victor J. Evans*

ATTORNEY

UNITED STATES PATENT OFFICE.

THOMAS W. THOMPSON, OF FREELAND PARK, INDIANA.

BLACKBOARD CLEANER.

Application filed October 28, 1925. Serial No. 65,453.

In the class rooms of schools the black boards are generally cleaned by the ordinary erasers. This method is not altogether satisfactory as the eraser becomes impregnated 5 with the chalk dust and is not effective in the cleaning operation but a greater objection is the fact that the chalk dust is circulated throughout the class room during such cleaning operation and inflicts injury on the 10 throats and nostrils of the teacher and pupils.

The object of this invention is the provision of means whereby a spray of water may be forcibly directed over the black boards to effect the cleaning thereof and wherein 15 said water is allowed to drip through the reticulated covering of a trough that has its outlet end connected with a sewer, the said cover of the trough providing a rest for the chalk sticks and for the usual erasers.

20 A further object is the provision of a means for this purpose which may be readily installed, easily operated and not liable to breakage or disorder.

To the attainment of the above broadly 25 stated objects and others which will appear as the nature of the invention is better understood, reference is to be had to the drawings which accompany and form part of this application.

30 In the drawings:

Figure 1 is a face view of the improvement. Figure 2 is a sectional view approximately on the line 2—2 of Figure 1.

A side wall of a class room is in the drawings indicated by the numeral 1. The black board is indicated by the numeral 2. The black board has its top secured to a longitudinal cleat 3 and the said black board is arranged at an outward angle with respect to 35 the wall 1 as disclosed by Figure 2 of the drawings. The angular arrangement of the black board 2 is obtained by the contacting engagement of the inner and lower edge thereof with the inner wall 4 of a trough 5.

40 The bottom of the trough is arranged at an angle and the deepest portion of the trough has connected thereto an outlet pipe 6 which in turn is connected to a sewer pipe or directly to the sewer in the school building.

45 The trough, adjacent to its open top, is formed with cleats or flanges that provide a rest for a reticulated frame 7. This frame supports thereon the eraser and the chalk sticks.

50 The numeral 8 designates the water inlet pipe. This pipe may enter the class room

from the floor or from the ceiling thereof and the flow of water through the pipe 8 is controlled by a hand operated valve 9. The pipe 8 may have branches that provide conductors for water into other class rooms. The pipe 8 is connected, at one end, to a longitudinally extending pipe 10 and is arranged above the black board 2, the said pipe 10 being supported by suitable brackets 11. 55 The outlet end of the pipe 10 is coupled to a downwardly directed pipe 12, the said pipe 12 having a valve controlled branch 13, coupled to the outlet pipe 6. The lower end of the pipe 12 has connected thereto a faucet 14. The faucet may supply water to the class room and may have a hose attached thereto in case of fire occurring in the class room or in any other places of the school.

The black board, as disclosed by Figure 1 75 of the drawings, is divided into sections, which for distinction are indicated in Figure 1 by the numerals 15 and 16, respectively.

Connected by suitable couplings to the pipe 10 there are valve controlled pipes 17 directed 80 downwardly toward the respective sections 15 and 16 of the black board 2. The pipes 17 are secured by brackets 18 to the cleat 3, and the respective series of the pipes 17 are coupled to longitudinally extending pipes 85

19. The pipes 19 may provide separate members or there may be a plug stopping the passage between the pipes 19 at the juncture of the black board sections 15 and 16. The pipes 19 have their lower inner faces pro-

90 vided with longitudinal series of apertures 20 and whereby water, when let through the pipe 8 and the pipes 17 will be directed against the faces of either or both of the black board sections in accordance with the opening or 95 closing of the valves that control the passages through the pipes 17. Secured on the top of the cleat 3 there is an upwardly and downwardly curved preferably metal guard 21.

The lower and outer end of the guard is disposed below the cleat and slightly out of contact with the black board 2. Of course, the guard is provided with openings through which the pipes 17 pass. The guard 21 prevents the outward splashing of water let 100

105 through the apertured or perforated pipes 19 and directs the water forcibly against the faces of the black board so that the same will be effectively cleaned.

By a device as above described, black boards 110 may be easily and effectively cleaned by the janitor of a school building after school hours,

and the liability of the circulation of dust from the chalk sticks will be effectively prevented. In order to flush the trough 5 there is arranged between the pipe 8 and the reduced end of the said trough a valve controlled pipe 22.

The valve of pipe 22 controlling the flow of water to the chalk trough may be adjusted so that the water will run into the trough 10 while the boards are being used, thereby keeping the trough flushed and clear of chalk dust without interfering with the use of the board.

The simplicity and advantages of the construction will, it is thought, be perfectly apparent to those skilled in the art to which such inventions relate, when the foregoing description has been carefully read in connection with the accompanying drawings. It

is to be understood that I am not to be restricted to the precise details herein recited and am entitled to such changes therefrom as fairly fall within the scope of what I claim without departing or sacrificing any of the advantages of the invention.

Having described the invention, I claim:

A cleaning system for blackboards comprising a blackboard having its lower edge spaced from the wall to thereby set the blackboard at an angle to the vertical, a perforated 30 water pipe connected to a water supply system arranged at the top of the blackboard, a metal guard enclosing the water pipe whereby the water striking the guard is forcibly directed against the blackboard.

In testimony whereof I affix my signature.
THOMAS W. THOMPSON.
